UNITED STATES PATENT OFFICE.

MERRILL LEE JAMES, OF SAN FRANCISCO, CALIFORNIA.

INDICATOR.

1,216,456.

Specification of Letters Patent. Patented Feb. 20, 1917.

Application filed August 21, 1915. Serial No. 46,691.

To all whom it may concern:

Be it known that I, MERRILL LEE JAMES, a citizen of the United States, residing at San Francisco, in the county of San Francisco and State of California, have invented certain new and useful Improvements in Indicators, of which the following is a specification, reference being had to the accompanying drawings.

10 This invention relates to certain improvements in indicators and has relation more particularly to a device of this general character especially designed and adapted for use in connection with vehicles whereby the 15 direction of turn may be readily and conveniently disclosed; and it is an object of my invention to provide a novel and improved indicator comprising two relatively movable members traveling in a path transverse of 20 the vehicle to which it is applied and capable of independent operation.

The invention consists in the details of construction and in combination and arrangement of the several parts of my improved indicator whereby certain important advantages are attained and the device is rendered simpler, less expensive and otherwise more convenient and advantageous for use, all as will be hereinafter more fully set 30 forth.

The novel features of the invention will be carefully defined in the appended claims.

In order that my invention may be the better understood, I will now proceed to describe the same with reference to the accompanying drawings, wherein—

Figure 1 is an elevational view of a somewhat diagrammatic character illustrating an indicator constructed in accordance with 40 an embodiment of my invention;

Fig. 2 is an enlarged fragmentary view, partly in section and partly in elevation, illustrating certain details of the invention as disclosed in Fig. 1;

Fig. 3 is a sectional view taken substantially on the line 3—3 of Fig. 2;

Fig. 4 is a sectional view taken substantially on the line 4—4 of Fig. 2;

Fig. 5 is a sectional view taken substantially on the line 5—5 of Fig. 2, and Fig. 6 is a sectional view through the outer end of the tubular member as herein embodied.

As disclosed in the accompanying drawings, 1 denotes a tubular member adapted to be disposed transversely of a vehicle and herein disclosed as suitably secured to the

dash D, although I wish it to be particularly understood that I am not limited to the part of the vehicle to which my device may be applied.

Depending from the tubular member 1 at substantially its longitudinal center and in communication with the bore of said member is a casing 2 having mounted therein the shaft 3 to which is affixed a gear wheel 4 in mesh with the rack member 5 of predetermined dimensions, the extremities of said rack being provided with the upstanding yokes 6 adapted to coact with the endwise movable members 7 and 8 positioned within the tubular member 1 and to be hereinafter more particularly referred to. The shaft 3 has also affixed thereto a sprocket wheel 9 of predetermined diameter and operatively engaged with the chain 10, the extremities of 75 which are suitably connected with the operating levers 11 whereby it will be perceived that the direction of rotation of the gear 4 may be as desired.

The endwise movable members 7 and 8 have their inner or adjacent extremities arranged in overlying relation and preferably with the member 7 telescoping the member 8 and the member 8 has secured to the periphery thereof the annular stop 12 and has also disposed therearound but free thereof the second annular stop 14 which is secured to the member 7 through the medium of the pins 15 disposed through the longitudinally disposed slots 16 provided in the member 8 whereby the stop 14 is secured to and movable with the member 7. Interposed between the stops 12 and 14 is the expansible member 17, herein disclosed as a conventional coil spring, surrounding the member 8 90 whereby the members 7 and 8 are normally at the limit of their movements inwardly of the tubular member, said limit of inward movement of each of the members being controlled by the annular shoulder 18 produced adjacent the outer extremity of each of said members 7 and 8 and coacting with the annular shoulder 18^a suitably arranged within the tubular member 1. The yokes 6 are adapted to engage the stops 12 and 14 whereby it will be perceived that upon endwise movement being imparted to the rack 5, one of the members 7 or 8 will be caused to move 100 in the same general direction whereby the indicator 19 carried by the outer extremity 105 of said member will be projected from within the tubular member 1 a distance suffi-

ciently to one side of the vehicle as to give a warning as to the direction of turn the vehicle is to make.

It will be readily appreciated that the expansible member 17 normally maintains the members 7 and 8 confined within the tubular member 1 and in order to facilitate the movements of said members 7 and 8, I find it of advantage to interpose therebetween 10 suitable anti-friction means, as indicated at 20, and to have the outer extremities of the bore of the tubular member 1 provided with the anti-friction means 21, as is believed to be clearly shown in the accompanying drawings.

I also find it of advantage in practice to provide each of the shoulders 18 with a facing of rubber or other compressible body to serve as a shock absorber for a purpose 20 which is believed to be clearly apparent to those skilled in the art to which my invention appertains.

From the foregoing description, it is thought to be obvious that an indicator constructed in accordance with my invention is of an extremely simple and comparatively inexpensive nature and is particularly well adapted for use by reason of the convenience and facility with which it may be assembled.

30 I claim:

1. A device of the character described comprising a tubular member, members disposed therein and capable of endwise movement, the adjacent extremities of said members being in overlying relation, a collar carried by each of said members, an expansible member interposed between said collars for normally maintaining the members substantially confined within the tubular member, 40 and means for imparting outward movement to said members.

2. A device of the character described comprising a tubular member, members disposed therein and capable of endwise movement, the adjacent extremities of said members being in overlying relation, a collar carried by each of said members, an expansible member interposed between said collars for normally maintaining the members substantially confined within the tubular member, an additional member mounted for reciprocatory movement within the tubular member engageable with the stops of the second named members, and means for reciprocating 50 said last named member.

3. A device of the character described comprising members capable of endwise movement, the adjacent extremities of said members being in overlying relation, a col-

lar carried by each of said members, an 60 expansible member interposed between said collars for normally maintaining the members at the limit of their inward relative movement, and means for imparting outward movement to said members.

4. A device of the character described comprising members capable of endwise movement, the adjacent extremities of said members being in overlying relation, a collar carried by each of said members, an expansible member interposed between said collars for normally maintaining the members at the limit of their inward movement, 70 an elongated member provided with upstanding yokes embracing the first named 75 members and coacting with the collars for limiting the movement of the members under the influence of the expansible member, and means coacting with the elongated member for moving the same in either direction. 80

5. A device of the character described comprising members capable of endwise movement, the adjacent extremities of said members being in overlying relation, a collar carried by each of said members, an expansible member interposed between said collars for normally maintaining the members at the limit of their inward movement, 85 an elongated member provided with upstanding yokes embracing the first named 90 members and coacting with the collars for limiting the movement of the members under the influence of the expansible member, said elongated member constituting a rack, 95 a gear in mesh therewith, and means for rotating the gear in either direction.

6. A device of the character described comprising tubular members in telescoping relation, the outer member being provided with a longitudinally disposed slot, a collar 100 fixed to the outer member, a second collar surrounding the outer member but free therefrom, means coacting with the inner member and the second named collar and disposed through the slot of the outer member 105 for fixing said second collar and the inner member, an expansible member surrounding the outer member and interposed between the collars for normally maintaining the members at the limit of their inward relative movement, and means for imparting outward movement to said members. 110

In testimony whereof I hereunto affix my signature in the presence of two witnesses.

MERRILL LEE JAMES.
